UNITED STATES PATENT OFFICE.

FRED MEYER, OF BURLINGTON, IOWA, ASSIGNOR TO DODSON VENDING MACHINE COMPANY,
OF DES MOINES, IOWA, A CORPORATION OF IOWA.

COIN-SLOT MECHANISM.

No. 921,553.

Specification of Letters Patent. Patented May 11, 1909.

Application filed November 19, 1908. Serial No. 463,483.

To all whom it may concern:

Be it known that I, FRED MEYER, a citizen of the United States of America, and resident of Burlington, Des Moines county, Iowa, have invented a new and useful Coin-Slot Mechanism, of which the following is a specification.

The object of this invention is to provide an improved construction for coin slot controlling devices or mechanism, whereby a coin slot is closed against the introduction of a coin when the machine is empty, whereby spurious coins subject to magnetic influence may be withdrawn prior to the possible entrance of said coins to operative position in a coin controller, and whereby the thickness of coins may be tested and those which are too thin may be discarded.

A further object of this invention is to provide coin slot closing devices adapted to be acted upon by articles to be dispensed in a vending machine in such manner that said devices are held in open position so long as any of such articles are contained in the machine, and are permitted to close whenever the machine is empty of the articles to be vended.

My invention consists in the construction, arrangement and combination of elements hereinafter set forth, pointed out in my claims and illustrated in the accompanying drawing, in which—

Figure 1 is a plan of the interior or working parts of the machine, together with a plan of the exterior of the machine in so far as it relates specifically to the coin slot closing devices. Fig. 2 is a side elevation, partly in section, of the operative parts of the machine, in so far as they relate to vending devices, coin slot closing devices, and connections between the vending devices and the other mechanism for closing the slot when the machine is empty. Fig. 3 is a side elevation, partly in section, illustrating the means employed for closing the coin slot. Fig. 4 is a vertical sectional view illustrating the means employed for closing the slot, for opening the slot, and for testing the coin in respect of the material of which it is made and its thickness. Fig. 5 is a plan of the coin slot closing devices taken on a plane beneath the slot plate or cover of the machine.

In the construction of the device as shown, the numeral 10 designates a supporting frame composed of a plurality of posts, bars and

cross-bars suitably connected and provided with bearings wherever desired. The entire frame 10 may be inclosed in a suitable casing, such as is described and illustrated in my companion application relating to cigar 60 vending machines. A shaft 11 is mounted for rotary oscillation in a horizontal plane in the frame 10. A block 12 is rigidly mounted on the shaft 11 near one end thereof. A shaft 13 is journaled for rotation in the frame 65 10 at right angles to the shaft 11 and in alignment with the central portion of the block 12. A crank-arm 14 is fixed to one end portion of the shaft 13 and a pin 16 is pivoted at one end in a slot in the block 12 and extends 70 through the outer end portions of the crank-arm 14.

The pin 15 is adapted to move to and fro in the slot in the block 12 and at the same time that end portion of the pin which passes 75 through the crank-arm 14 is adapted to be moved by said crank-arm in a circle. The result of such movement is an up-and-down oscillation of the extreme end of the block 12, thus effecting the oscillation of the shaft 11 80 through an arc approximating to one-quarter revolution. A sleeve 16 is mounted for rotation in the frame 10 and is adapted to receive the outer end portion of the shaft 13. A crank-arm 17 is fixed to the outer end portion of the sleeve 16 and said crank-arm is 85 designed to be located outside of any casing employed to inclose the remaining mechanism and devices. A pin 18 is fixed to and projects radially from the shaft 13 and is 90 adapted to be engaged by a pawl 19 pivoted on the inner end portion of the sleeve 16. A stop 20 in the sleeve limits movement of the pawl 19 in one direction, so as to present said pawl for operative contact with the pin 18 95 whenever the sleeve 16 is rotated in the desired direction by the crank 17, as indicated by the arrow *a* in Fig. 1.

A jaw-frame 21 is pivoted on the frame 10 and the axis of articulation of the jaw-frame 100 is parallel with the axis of the shaft 13 and at right angles to the axis of the shaft 11. A cross-bar is fixed to and extends transversely of the upper end portion of the jaw-frame 21 and also projects rearward therefrom. Loops 105 or hinge members 23, 24 are mounted in the cross-bar 22 and are formed with eyes above and below said cross-bar. Jaws 25, 26 are pivoted on the loops or hinge members 23, 24 below and above the cross-bar 22 by means 110

of rods 27, 28. The jaws 25, 26 extend rearward from the rods 27, 28 and have teeth on their inner ends extending upwardly and downwardly respectively. The jaw-frame is 5 adapted to be moved rearward and cause the teeth of the jaws 25, 26 to pass between cutting devices and engage cigar cells 29 in a holder 30 beneath a holder frame 31. The holder 30 is formed on the frame 10 and the 10 holder frame 31 is pivoted on the frame 10 and there adapted conjunctively for temporary holding of cigar cell series preliminary to the engagement therewith of the jaws. Each cell is supposed to contain a cigar 32, 15 and a series of the cells is contained in a box 33 suitably mounted within the frame 10 at the rear of the jaw-frame. Suitable devices are mounted on the jaw-frame and on the shaft 11 for operating the jaw-frame and the 20 jaws thereon to engage and remove cigar cells in series from the holder 30 and holder frame 31, and suitable devices are operated by said shaft to sever the cigar cell series at predetermined times. These devices are 25 illustrated, described and claimed in my companion applications pending concurrently herewith. A plate 62 is adapted to be mounted on the top of the casing employed to contain the mechanisms and said plate is 30 formed with a coin slot 63. A bell-crank latch 64 is pivoted on the plate 62 and one arm thereof normally covers the coin slot 63. A knob 65 is formed on one arm of the bell-crank latch 64 by means of which said latch 35 can be manipulated. The latch 64 is held in closed position over the slot 63 by a spring 66 and a stop 67 projecting upward from the plate 62 limits movement of said latch under the influence of the spring. A stop 68 projecting upward from the plate 62 limits 40 movement of the latch 64 in opposition to the spring under manual actuation. A coin passage 69 extends downward from the slot 63 and is open at top and bottom. One side 45 of the coin passage 69 is formed by a plate 70 rigidly fixed to the plate 62, and the opposite side of said coin passage is formed by a plate 71 pivoted at its rear end on a pin 72 which serves as a pivot for the bell-crank latch 64. 50 The latch is secured to the upper end of the pin 72 by a transverse pin 73 and the plate 71 is connected to said pin 72 by a coil spring 74 at one end whereby the pivotal movement of the plate on the pin is cushioned. The 55 tendency of the spring 74 is to move the plate 71 away from the plate 70, and such tendency is limited and overcome by a hook 75 on said plate 70. The outer end portion of the plate 70 is turned inward to form a flange 60 76 adapted for engagement with the plate 71 at times. The length of the flange 76 is identical with the thickness of a proper coin or nickel five-cent-piece. A gate 77 is mounted rigidly on the pin 72 and is adapted 65 to be moved by said pin to and fro through

an arc beneath the plates 70, 71 and intersect the coin passage 69. A stud 78 is fixed to and extends upward from the central portion of the gate 77 and is adapted to engage the plate 71 at times and move said plate 70 toward the plate 70 against the resilience of the spring 74. Ears 79 are formed on and extend laterally from the rear end portion of the plate 70 and a latch 80 is pivoted at its rear end on a pin 81 vertically mounted 75 in said ears. The latch 80 is formed with a flange or lip 82 adapted to extend across the upper face of the plate 70 and intersect the coin passage 69 at its initial end adjacent the coin slot 63. 80

A coil spring 83 is mounted on the pin 81 and tends to move the latch 80 away from the plate 70 and hold the flange or lip 82 out of the coin passage. An arm 84 is formed on and extends at right angles to 85 the latch 80 and is pivoted to the forward end of a lever 85. The lever 85 is formed with a slot 86 in its rear end adapted to receive a pin 87 on a crank-arm 88. The crank-arm 88 is fixed to and rises from a 90 horizontal rod 89 arranged for oscillation on the frame 10 of the machine. The rod 89 is oscillated and held normally in one direction by a spring 90 connecting the arm 88 to a stationary portion of the frame 10, 95 and may be moved in the opposite direction by elevation of a holder frame 31 fixed thereto and extending forward in such position as to be engaged and raised by a cigar 32 in a holder 30. Or the rod 89 may be 100 moved against the resilience of the spring 90 by a lever 94 attached to one end thereof and extending downwardly and forwardly across the jaw-frame 21 of the machine. Thus, when the cigar-holder 30 is empty, 105 the holder frame 31 will fall toward said holder and in so doing will move the rod 89, arm 88 and lever 94 into the positions shown by dotted lines. In such positions the arm 88 carries the pin 87 forward and causes 110 said pin to move the rod 85 forward and swing the latch 80 in such manner that the lip 82 will intersect the coin passage 69 and prevent the insertion of a coin to the machine through the slot 63. But when 115 the holder frame 31 is upheld, either manually through the lever 94, or by a cigar in the holder 30, the latch 80 is held away from the plate 70 and the lip 82 is held out of the coin passage 69. A coin chute 95 120 leads from the coin passage 69 to the entrance of the coin controller.

An opening is formed in the upper end portion of the coin chute 95 communicating with a discharge chute 96, which discharge 125 chute extends forward and downward on helical lines to a discharge spout or cup 97 on the exterior of the casing of the machine. A magnet 98 is mounted at the upper end of the coin chute 95 and one arm of said 130

magnet is longer than the other and extends across the upper end of the opening in the front of said chute and is beveled and curved rearwardly on its lower face. A 5 gate 99 is pivoted on a screw 100 on the coin chute 95, and an arm 101 is formed on and beveled downwardly and forwardly from the upper end of said gate and extends across said coin chute 95. A spring 102 mounted on the screw 100 tends to hold 10 the gate 99 inward in such position that the arm 101 thereof will extend in inclined position across said coin chute and guide an object thereon in rolling motion to the 15 discharge chute 96. The lower end portion of the gate 99 extends within the orbit of travel of a moving part of the coin controller and is adapted to be engaged thereby and moved into the position shown in Fig. 2, 20 when the handle 17 is in proper position (directed upwardly) for the insertion of a coin to the machine. It has been explained that when the cigar-holder is empty, the 25 latch 80 closes the coin slot and prevents the insertion of a coin until the bell-crank latch 64 is opened by manual actuation. When the handle 17 is not directed upwardly and the cigar-holder contains a cigar, a coin can be introduced through the coin 30 slot 73 to the passage 69 and will be discharged out of the passage 73 into the chute 95. If the coin or check is spurious and subject to magnetism, it will be engaged by the projecting end portion of the magnet 35 net 98 and will roll beneath the rounded or beveled portion thereof into the discharge chute 96. If the coin is of proper thickness but the handle is not in proper position, it will be retained until the bell-crank latch 40 64 is released, and then it will fall upon the arm 101 and be directed by said arm to the discharge chute 96 and thence to the cup 97 outside the machine, where it can be repossessed by the operator. If the 45 handle is in proper position and the coin or check is not subject to magnetism, then upon the releasing of the plates said coin will fall through the chute 95, the gate being oscillated to move the arm 101 out of 50 the way because of the proper positioning of the plate 45 and shoulder 103. The coin will continue through the chute 95 and coin controller into a position to be employed to connect moving parts of the coin controller 55 and operate the feeding devices.

I claim as my invention—

1. In a cigar-vending machine, a slot-

plate, a bell-crank latch pivoted on said plate and springheld in one direction, stops on said plate limiting movement of said 60 latch in either direction, a gate pivoted beneath said slot-plate and springheld in one direction, an arm pivoted to said gate, a shaft mounted for oscillation, an arm on said shaft engaging the first arm and springheld 65 in one direction, and a cigar-holder attached to said shaft.

2. In a cigar-vending machine, a slot-plate, a bell-crank latch-plate pivoted thereon and adapted to cover the slot, said 70 latch-plate normally held in closed position by a spring, a gate pivoted beneath said slot-plate and adapted to close said slot, a slotted bar pivoted to said gate, a holder frame mounted for oscillation, and connections between said holder frame and slotted 75 bar.

3. In a cigar-vending machine, a plate formed with a slot, a latch-plate pivoted thereon and springheld in closing position, a 80 gate pivoted beneath the slot-plate and springheld in position to close said slot, a slotted arm leading from said gate, a rod, an arm connecting said rod and slotted arm and springheld in one direction, and a holder 85 frame fixed to said rod and adapted to be raised and lowered either manually or by a cigar passing beneath said frame.

4. In a cigar-vending machine, a plate formed with a slot, a gate pivoted beneath 90 said plate and adapted to close said slot at times, said gate springheld in one direction, a slotted arm pivoted to said gate, and means acted upon by a cigar in a holder whereby said slotted arm is caused to move said gate 95 into open position.

5. In a cigar-vending machine, a plate formed with a coin slot, a gate pivoted beneath said plate and springheld in position to close said slot, a slotted bar pivoted to 100 said gate, a rod mounted for oscillation, connections between said rod and slotted bar, a holder frame on said rod adapted to be engaged by successive cigars in movement through the machine, and a lever attached to 105 said rod and adapted for manual actuation to raise said holder frame.

Signed by me at Burlington, Iowa, this 16th day of November, 1908.

FRED MEYER.
